UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION-GEAR.

1,287,403.

Specification of Letters Patent. Patented Dec. 10, 1918.

Application filed February 26, 1917. Serial No. 151,005.

To all whom it may concern:

Be it known that I, JOHN F. O'CONNOR, a citizen of the United States, residing at Chicago, in the county of Cook and State of Illinois, have invented a certain new and useful Improvement in Friction-Gears, of which the following is a full, clear, concise, and exact description, reference being had to the accompanying drawings, forming a part 10 of this specification.

This invention relates to improvements in friction gears.

One object of the invention is to provide a friction gear for railway draft riggings having high capacity and certain release.

Another and more specific object of the invention is to provide a friction gear of the type above indicated wherein are employed wedges and friction shoes so arranged that 20 the pressure from the wedges is well distributed to the shoes to thereby avoid concentration of the pressure on the shoes at a few points with the resultant improper action.

25 In the drawing forming a part of this specification, Figure 1 is a longitudinal vertical section of a portion of a draft rigging, showing my improvements in connection therewith. Fig. 2 is a front end elevation 30 of the friction gear proper shown in Fig. 1. Fig. 3 is an enlarged transverse vertical sectional view of the friction gear taken substantially on the line 3—3 of Fig. 1. Figs. 4, 5 and 6 are views corresponding respectively to Figs. 1, 2 and 3, but illustrating another embodiment of the invention, Fig. 6 being taken on the line 6—6 of Fig. 4. And Figs. 7, 8 and 9 are views corresponding to Figs. 1, 2 and 3 illustrating a still different 40 embodiment of the invention, Fig. 9 being taken on the line 9—9 of Fig. 7.

Referring first to the construction illustrated in Figs. 1, 2 and 3, 10 denotes the draw bar of a draft rigging to which is secured a yoke 11, the gear designated generally by the reference A being confined within the yoke and between front follower 12 and rear follower 13, said followers cooperating with the usual stops on the draft 50 sills, as will be understood.

The improved friction gear proper, as shown, comprises a combined friction shell and spring casing 14, a plurality of circularly arranged friction shoes 15 coöperable 55 with the shell, a series of wedge members 16,

a central wedge block 17, a series of inner wedge elements 18, a spring follower 19, and a main spring 20 preferably consisting of an outer heavy coil and nested lighter inner coil.

The friction shoes are provided with cylindrical outer friction surfaces to coöperate with the corresponding friction surfaces of the shell in a well known manner. Each of the shoes 15 is provided on its inner face 65 with an inclined wedge surface 21 with which co-acts the adjacent wedge face 22 of the corresponding wedge member 16, it being understood that there is one wedge member 16 for each shoe 15. On their inner faces, 70 the wedge members 16 are also provided with wedge faces 23 which extend rearwardly and outwardly with respect to the axis of the gear and directly co-act with the correspondingly arranged outer wedge faces 75 24 on the central block 17. The friction shoes are also each provided at their inner ends with forwardly and inwardly inclined wedge faces 25 with which directly co-act the correspondingly disposed outer wedge 80 faces 26 of the wedge elements 18, there being one of the latter for each of the friction shoes. Each of the wedge elements 18 is also provided on its inner face with a forwardly and outwardly inclined wedge surface 27 85 which directly co-acts with a correspondingly disposed wedge face 28 on the rear portion of the wedge block 17. A retaining bolt 29 is extended through suitable perforations in the rear wall of the friction shell, spring 90 follower 19 and wedge block 18.

In buffing movement, pressure is transmitted directly from the front follower 12 to the wedge members 16 and from the latter outwardly to the friction shoes through 95 the wedge faces 21 and 22. Upon inward movement of the wedge members 16 relatively to the other elements of the friction gear, it is apparent that the central wedge block 17 will be forced inwardly, thus causing the inner wedge elements 18 to move outwardly or radially, the wedge elements 18 in this movement bearing against the inner ends of the friction shoes on the wedge faces 25. The movement of all the parts 105 is, of course, resisted by the spring 20, through the follower 19. With the action above described, it is apparent that radial pressure is transmitted to the friction shoes from both the wedge members 110

16 and wedge elements 18 and this radial pressure is applied over a relatively large area of the shoes and at the outer and inner ends, thus eliminating any tendency for the 5 friction shoes to rock or be loose with respect to the friction shell at any point. It is also apparent, that by varying the various angles of the contacting wedge faces, the outward pressure can be made as high as 10 necessary and at the same time a certain release is insured since the wedge members 16 with the central block 17 will easily disengage from the friction shoes because of the flare or bell mouth formed by the wedge 15 surfaces 21 of the friction shoes.

In the construction illustrated in Figs. 4, 5 and 6, the combined friction shell and spring casing A' and spring therewithin are the same as shown in the other views. Co- 20 operating with the friction shell A' are friction shoes 115 arranged in a circular series, each of the friction shoes 115 having an inner rearwardly and inwardly inclined wedge face 121 with which co-acts the correspondingly arranged wedge face 122 of a wedge member 116, there being one of the latter for each of the friction shoes. Each of the wedge members 116 is provided at its inner end with a rearwardly and outwardly inclined wedge face 123 with which co-acts the correspondingly disposed wedge face 124 of a central wedge member or block 117. In this construction, the outer heavy coil of the spring 120^a directly engages the friction 35 shoes whereas the inner lighter coil 120^b directly engages the block 117.

The operation of the construction shown in Figs. 4, 5 and 6 will be apparent from the preceding description of the operation of 40 the structure shown in the other figures except that, in release, the inner coil 120^b of the spring will directly assist in forcing the wedge elements outwardly.

In the construction illustrated in Figs. 7, 45 8 and 9, the combined friction shell and spring casing A² is similar to those illustrated in the other figures and coöperable therewith are friction shoes 215, each of the latter being provided at its outer end with 50 a rearwardly and inwardly inclined wedge face 221 and at its inner end with an inwardly and forwardly inclined wedge face 125. In this construction also, there are wedge members 216, one for each shoe, and 55 each wedge member 216 is provided on its outer face with an inwardly and rearwardly inclined wedge face 222 that co-acts with

the adjacent wedge face 221 of the friction shoe. Each of the wedge members 216 is further provided at its inner end with an inwardly and forwardly inclined wedge face 223 with which co-act correspondingly inclined wedge faces 224 of an inner wedge element 218. The latter also engages the inner wedge faces 125 of the friction shoes. 60 A detailed description of the operation is not believed necessary in view of that given for the construction shown in Figs. 1, 2 and 3.

I claim:

1. In a friction shock absorbing mechanism, the combination with a friction shell, friction shoes coöperable with the shell, and spring means, said friction shoes having inwardly and rearwardly inclined wedge faces 75 at their forward ends and inwardly and forwardly inclined wedge faces at their inner ends, of wedge members co-acting with the wedge faces at the forward ends of said friction shoes, and separate wedge means 80 co-acting with the wedge faces at the inner ends of the friction shoes, said wedge means being actuated with respect to the friction shoes by said wedge members.

2. In a friction shock absorbing mechanism, the combination with a friction shell, a circularly arranged series of friction shoes coöperable therewith, each of said shoes having oppositely extending wedge faces on its interior, and spring means, of a 90 plurality of wedge members co-acting with the friction shoes at their outer ends, a plurality of wedge elements co-acting with the friction shoes at their inner ends, and a wedge block interposed between said wedge members, and wedge elements.

3. In a friction shock absorbing mechanism, the combination with a friction shell, a circularly arranged series of friction shoes coöperable therewith, each of said shoes having oppositely extending wedge faces on its interior, and spring means, of a plurality of wedge members co-acting with the friction shoes at their outer ends, a plurality of wedge elements co-acting with the friction 100 shoes at their inner ends, and a wedge block interposed between said wedge members and wedge elements, the number of said wedge members and wedge elements corresponding to the number of friction shoes.

In witness that I claim the foregoing I have hereunto subscribed my name this 15th day of Feb., 1917.

JOHN F. O'CONNOR.
